VOTING MACHINE

Ransom F. Shoup, Bryn Mawr, and Edward A. Fox, Sr., Morton, Pa., assignors to Shoup Research and Development Corporation, Ridley Park, Pa., a corporation of Pennsylvania

Filed Nov. 10, 1960, Ser. No. 68,411

2 Claims. (Cl. 235—54)

This invention relates to a voting machine of the type disclosed in prior Shoup patents, such as Patent No. 2,054,102 and No. 2,826,356, and other Shoup patents which are available for inspection in the United States Patent Office.

Patent 2,054,102 discloses a voting machine which includes a number of vertical columns of voting spindles, and a ballot assembly including a backing plate (31); a ballot (33); a protector (32); and shutter (34) associated with each of said columns of voting spindles. The ballot assemblies referred to were inserted downwardly through slots (36) provided in the top of the machine. See FIGS. 6, 7, 15 and 21, and line 60, et seq., left-hand column, page 3, of Patent 2,054,102.

The ballot assemblies are about 40 inches long and the machine itself is over five feet high. Therefore, the assemblies could not be inserted downwardly into the machine except in a room having a sufficiently high ceiling. Since in most modern buildings the average ceilings are about eight feet high, it was necessary to tilt the large and heavy voting machine on its side to permit insertion of the ballots and their covers.

It is therefore the object of this invention to produce an improved voting machine of the type set forth in which the plates and shutters are non-removable and in which the flexible, transparent paper ballot and the flexible protector are readily insertable into position in any room in which a machine can be placed in upright position without having to tilt the voting machine on its side.

A further object of the invention is to provide means to permit insertion of the ballot, and its flexible transparent cover, at a point near the bottom of each column of voting spindles and to provide an access door which is closed while the machine is being used and which can be opened only when the machine is not in use, or after the voting is completed to permit the removal of the ballots, the resetting of the machine, and the insertion of new ballots for use in a subsequent election.

The full nature of the invention will be understood from the following specification and the accompanying drawings in which:

FIG. 1 is a fragmentary, and diagrammatic, front elevational view of a voting machine shown in Shoup Patent, No. 2,826,356, but embodying the improvements of the present invention.

FIG. 2 is an enlarged, exploded, fragmentary view showing the parts of said voting machine with which the parts constituting the present invention co-act.

FIG. 3 is a fragmentary, enlarged, sectional view looking in the direction of line 3—3 on FIG. 1.

FIG. 4 is an enlarged, sectional view looking in the direction of line 4—4 on FIG. 1.

FIG. 5 is similar to the upper portion of FIG. 4, except that it shows how the flexible, transparent cover of the ballot is inserted over the paper ballot, which was similarly inserted.

FIG. 6 is an enlargement of the lower portion of a ballot and its cover, showing details of construction.

FIG. 7 is an enlarged section looking in the direction of line 7—7 on FIG. 1.

Patent 2,826,356 discloses all of the elements of a voting machine with which the parts constituting the present

2

invention cooperate and therefore it is thought that, in the present disclosure, said elements may be designated with the same reference numerals with which they are designated in said patent without being described in detail and, in order to distinguish the reference numerals which are borrowed from the last-mentioned patent from the numerals used to designate the parts constituting the present disclosure, the former reference numerals are underlined.

However, in order to make reference to the Patent 2,826,356 unnecessary, it is pointed out that when lock 120, which is controlled by the election officer, is turned to the right, slide 102 is also moved to the right and pin 100 rides on cam 106, and that, when slide 102 is moved to the left, pin 100 rides on cam 104, for the purpose set forth in Patent No. 2,826,356. But, it will be noted that, when slide 102 is moved to the right, dog 114 engages ratchet 112 and therefore the slide can not be moved to the left unless lock 124, which is controlled by the custodian of the machine, is turned to the right to cause finger 126 to engage finger 128 and lift dog 114 out of engagement with the ratchet 112 on slide 102.

In carrying out our invention, we provide finger 126 of the custodian's lock 124 with a forwardly projecting pin 130 which is adapted to engage opening 132 in the adjacent end of a slide 134. Slide 134 is carried by pins 136 which are carried by a fixed wall 56 of the machine and which pass through slots 137 and 138 in slide 102 and plate 74, respectively, to engage slots 139 in slide 134, to support the slide and fingers 140 which are carried thereby, for lateral movement upon rotation of lock 124.

The lower ends of the ballots, and their covers, are protected by a door 142 which is hinged at 144 to a fixed wall 146 of the machine. Door 142 is provided with internal pendent plates 148 which, when slide 134 is moved to the left, register with fingers 140 on slide 134 to prevent movement of the door from the closed, solid line, to the open, broken line, position of FIG. 4.

A machine of the type referred to includes fixed, rigid strips 150 through which the voting spindles S project and moveable shutters 68 which are disposed between the strips and are moveable to cover, or uncover, the vote counters of the machine. The marginal portions of strips 150 are spaced from the adjacent supporting wall to form channels for receiving the vertical edges 152 of ballots 153 and the vertical edges 154 of the ballot covers 155. It will be seen from FIGS. 1 and 7 that the upper ends of the ballots and their covers are disposed behind the front wall 156 of the upper cover of the machine. In order to hold the ballots in position, we provide a spring plate 158 which carries a pin 160 which is disposed below the lower edge 162 of front cover 156, and on which the ballot is impaled. If desired, we also provide flat springs 164 which carry pins 166 for engaging the lower ends of the ballots.

The operation is as follows:

To insert the ballots, the custodian turns lock 124 to the right to move slide 134 to the right to take fingers 140 out of registration with lugs 148 on the door 142 to permit movement of the door to the open, broken line, position of FIG. 4. The old ballots, if any, and their covers, are removed, and the new ballots, and their covers, are inserted, upwardly, in the general manner shown in FIG. 5. It will be understood that when the ballot reaches its proper position, its upper end is engaged with pin 160 and its lower end is engaged with pins 166. The

transparent covers 154 are next inserted with their upper ends behind front wall 156 of the upper cover of the machine, as best shown in FIGS. 1 and 7. With the ballots and their covers in position and, assuming the machine is otherwise ready, door 142 is moved to its upper, closed position; the custodian turns lock 124 to the left to bring fingers 140 into registration with the lugs 148 on the door to lock the door in position, and the election officer turns lock 120 to the right to move slide 102 to the right so as to engage dog 114 with ratchet 112 in the manner, and for the purpose set forth in, the Patent 2,826,356.

What we claim is:

1. The combination with a voting machine of the type which includes at least one column of voting spindles, a slide movable to a first position, in which said voting spindles are useable, and to a second position, in which said voting spindles are locked against use, a first actuating means for moving said slide to either of said positions, retaining means automatically operable, upon movement of said slide to its first position, to lock said slide in said first position, a second actuating means for releasing said retaining means to permit movement of said slide to its second position, an elongated ballot, means on either side of said column defining an open ended channel for receiving said ballot, one end of said channel being closed to prevent access to the corresponding end of said ballot and the other end of said channel being open to permit insertion of said ballot into, and withdrawal of said ballot from, said channel, a door for closing said other end of said channel, a latching mechanism for locking said door in closed position, and means operatively connecting said latching mechanism to said second actuating means and operable upon engagement of said second actuating means with said retaining means to disengage said latching mechanism and permit opening of said door, said latch mechanism including:

5

10

20

25

30

35

35

an auxiliary slide, a finger carried thereby, a lug carried by the inner wall of said door and engageable with said finger, said lug and said finger being so related that movement of said slide to its second position disengages said finger and said lug.

2. A voting machine including:

a vertical column of voting spindles,

a mechanism movable to a first position in which said spindles are locked against use and to a second position in which said spindles are released for use,

a ballot bearing the names of candidates to be voted on,

a channel associated with said column of voting spindles and adapted to receive said ballot, the upper end of said channel being closed and the lower end thereof being open for the insertion and withdrawal of the ballot therethrough,

a door hinged about a horizontal axis below the lower end of said channel and movable to an upper position in which it obstructs the lower end of said channel and to a lower position in which the lower end of the channel is unobstructed,

a slide,

latch means carried by said slide and engageable with said door when the latter is in its upper position to lock said door in said position, and

means operatively connecting said slide for joint movement with said mechanism whereby, when said door is in its upper position, movement of said mechanism to its second position engages said latch means with said door.
